UNITED STATES PATENT OFFICE

2,679,781

COMBINED FALLBOARD AND STOP MOUNTING

James A. Koehl, Evanston, Ill., assignor to Central Commercial Industries, Inc., Chicago, Ill., a corporation of Delaware

Application October 2, 1952, Serial No. 312,709

4 Claims. (Cl. 84—179)

1

This invention relates to a combined fallboard and stop support for pianos or similar musical instruments and particularly to pianos employing means for electrically producing organ, orchestral, and other sustained and percussive tones from the instrument's conventional keyboards. An instrument of this class is disclosed in my prior Patent No. 2,250,065, issued July 22, 1941. The term "stop" as used herein has reference to an electric switch which is usually manually operated at the will of the player for determining the timbre of the tone desired to be produced. Electric and pipe organs frequently have many of such stops and same are mounted upon the console in convenient reach of the player where they can be drawn and restored according as tonalities are to be suppressed or produced.

An object of the invention is the provision of a fallboard which can be readily adjusted from a position to uncover to a position to cover the keyboard as and when desired, which fallboard is formed, constructed, designed and adapted to support the "stops" in a horizontal role above the plane of the keyboard and otherwise so arranged that they can be conveniently manipulated as desired, yet will not occupy any portion of the keyboard that would shorten the playing surfaces of the keys or in any way obstruct or interfere with movements of the hands of the player.

A still further object is the provision of a fallboard and "stop" mounting which is compact and can be readily embodied in the case of a piano without material alteration in the construction thereof.

A still further object is a provision of a fallboard and "stop" mounting, which, when adjusted to cover the keyboard, will completely house the "stops" and give to the case of the piano the appearance of an instrument having none of the features of an electric organ.

A still further object is the provision of a fallboard and stop mounting, which, when adjusted to cover the keyboard, may be locked to the case of the piano to prevent access being gained both to the keyboard and the stops.

A still further object is the provision of a fallboard and "stop" mounting which is coactive with an "on" "off" electric switch to break the electrical circuit of the sustained tone producing system when closing the fallboard over the keyboard.

A still further object is the provision of a combined fallboard and "stop" mounting which is exceedingly simple, practical and of such form

2

and construction as will give to the instrument a neat and workmanlike appearance.

Other objects and advantages will appear from the following description and upon reference to the accompanying drawings, in which:

Figure 1 is a transverse section through a portion of the case of a piano showing my improved fall and "stop" mounting in its opened position of adjustment.

Figure 2 is a view similar to Figure 1 showing the fallboard closed, and

Figure 3 is a perspective view of a portion of a piano showing the fallboard opened.

In the accompanying drawings 10 represents a portion of the bed plank of a piano; 11 the playing-keys of the instrument's keyboard; 12 the usual key slip; 13 the key stop rail which limits upward pivotal motion of the keys and 14 a structural part of the instrument's case, the same providing with said stop rail an intervening, longitudinally disposed, forwardly facing opening 15 between these parts, the said opening having a length substantially coextensive with that of said keyboard. By this arrangement, it is proposed that the herein disclosed combination of coactive elements shall constitute a cover for the keyboard when the device is tilted to one possible position of angular adjustment and as a means for supporting a system of organ stops to dispose

30 same for manipulation as desired when the device is tilted to a second possible position of angular adjustment such as when the keyboard is completely uncovered. As will be explained later in this description, the arrangement of all coactive parts of the device provides a compact organization of elements including a system of organ stops which will be within the reach of the player with no part of the device extending into the plane of the keyboard where they would otherwise interfere with free movements of the hands of the player. It is also to be noted by the herein disclosed arrangement of parts, the organ stops will be disposed in such proximity to the keyboard of the instrument as will enable the hand

40 of the player to operate the stops without removing the hand from the keyboard. It is to be further noted that when the device is tilted to completely cover the keyboard the stop mechanism is completely housed between the keyboard and

45 50 the coactive elements of the device.

My improved fallboard and "stop" mounting comprises a longitudinally disposed casing 16 or receptacle-like structure which extends throughout the length of the stop rail 13 and is hinged to the stop rail at 14a to enable the casing to be

tilted from the vertical opened position shown at Figure 1 to the closed position shown at Figure 2.

The casing 16 is preferably rectangular in cross-section and essentially includes a vertical front panel 17, a rear panel 18, the latter suitably spaced apart from the front panel, and top and bottom strips 19 and 20.

Contained in the casing 16 is a frame 21 which contains a longitudinally disposed bus-bar 22 which is electrically coactive with resilient contactors 22a, one of which is shown at Figures 1 and 2. With particular reference to Figure 1, it is noted that the contactor extends from the hub 24 of a stop tablet 25. The casing 16 is formed at its front with a rectangular opening 26. Referring again to Figure 1 it is noted that tablet 25 is positioned in opening 26 that it can be conveniently manipulated by the hand of a player seated at the keyboard.

In practice, there will be any suitable number of electric stop switches and associated tabs as will be appreciated upon reference to Figure 3, and there will be connected to each separate contactor 22a a tone signal input lead 26. When the tablet 25 is tilted to the dotted line position shown at Figure 1, contact 22a engages the bus-bar 22 and tone signal voltage will be impressed on said bus-bar for conduction to an electro-acoustical translating system, not shown where it will be converted into audible sound for musical expression.

Hinged at 27 to panel 18 is a panel 28 which is not as wide as panel 18 but is coextensive therewith. Hinged to panel 28 as at 29 is a strip 30 and hinged to strip 30 as at 31 is a strip 32. Strips 30 and 32 are of the same width but less than that of panel 28. To this point in the description, it is noted that by mounting the casing 16 in the manner described, it is free to be moved through the opening 15 in the front of the case of the piano. When the fallboard is opened, it projects rearwardly into the case of the piano so that the front of the casing 16 is substantially flush with the structural panel 14 of the case of the piano. The skirt-like portion 33 of panel 17 freely rests against the front face of said panel 14, thus to give to the organization an attractive workmanlike appearance. The tablets 25 are now in a vertical plane and are so situated in front of the player as to enable the tablets to be manipulated at will. The tablets are also situated sufficiently in back of the effective playing surfaces of the keyboard so as to not interfere with full use of the keys and with no inconvenience to the player whatever.

When the fallboard is closed over the keyboard the casing 16 occupies the horizontal position shown at Figure 2, in which position, panel 28 and panel 18 lie in the same horizontal plane. strips 30 and 32 are vertically disposed with the lower edge of the strip 32 resting on the upper edge of rail 12. Thus, the casing is completely forwardly disposed and forms a housing for all stop switches. In order that the opening 15 will be closed when the fallboard is closed over the keyboard, strip 20 has secured thereto an apron which completely covers the opening 15 as shown at Figure 1.

All parts that go to form the casing 16 may be of wood. Such of their surfaces that are exposed to the eye will be finished the same as the woodwork which constitutes the case of the piano.

An instrument which makes desirable the use of stop mechanism may employ any well-known

type of means for producing tone signals at the frequencies of notes associated with different keys of the keyboard of a piano. Substantially the same system can be used as is disclosed in my prior Patent No. 2,250,065. Ordinarily, such systems receive their power from an alternating current line. When the line is connected in circuit with the instrument, the stop tablets may be operated so that a tone of any desired quality will speak at the pleasure of the player. It sometimes happens that the "on" "off" switch which controls distribution of electrical energy to the tone generators is accidentally left on after one has finished playing the instrument. The fallboard adapts itself well to means that will avoid any such thing happening if and when the fallboard is adjusted to a position to close the keyboard. The stop rail 13 is provided with an electric switch S. This is located in close proximity to an adjacent cheek piece C of the case of the piano. When the casing 16 is adjusted to close the keyboard, the casing engages the stop switch so as to break the current supply circuit. In this manner, the instrument is automatically electrically disabled until the fallboard is again restored to an opened position.

It frequently happens with electrical instruments that children tamper with parts that could be damaged. To avoid this, not only when the fallboard is closed but by means of the lock L, the fallboard may be so secured to the case of the piano as to prevent its being opened except by an authorized person.

While I have referred to a stop strip 13, this shall not be construed as in any manner limiting the invention. A stop strip in the sense intended herein is any portion of a piano case which is situated above the keys so as to stop the keys when they have reached their playing positions under the normal influence of the customary loading springs, not shown.

From the foregoing description it follows that the casing section 16 of the device opens forwardly when the keyboard is uncovered, whereas when the keyboard is covered, the opening in the casing extends downwardly where it faces the keyboard. In this position the rear panel 18 of the casing forms a closed back for the receptacle so that the stop mechanism is wholly concealed between said back and the keyboard when the latter is covered, all as will be understood upon reference to Figure 2 of the drawings.

What I claim as my invention is:

1. A combined keyboard cover and stop mounting for keyboard musical instruments, said combined cover and stop mounting comprising an organization of hingedly connected coactive sections formed, arranged and adapted to be tiltably mounted on the instrument's case to cover the keyboard when said organization is tilted in one direction and to uncover the keyboard when said organization is tilted in an opposite direction, one of said sections forming a hollow, receptacle, open at one side and closed at its opposite side; and an organ stop mechanism mounted in said receptacle forming section for manipulation as desired from the open side thereof when the keyboard is uncovered and to be wholly housed in the space between the keyboard and the hingedly connected coactive sections of said organization when the keyboard is covered.

2. A combined stop mounting and cover for the keyboard of a musical instrument employing a case upon which the keyboard is supported in a horizontal playing position, the front of said case,

at a point above the plane of the keyboard and slightly rearwardly of the back ends of the effective playing surfaces of the keys thereof having a longitudinally disposed forwardly facing opening extending the full length of said keyboard; said combined stop mounting and keyboard cover comprising a longitudinally disposed receptacle connected to said case for tilting adjustment through said opening from a vertical position rearwardly of the back ends of the effective playing surfaces of the keys of said keyboard to a horizontal position partly covering the keyboard; a manually actuatable stop mechanism mounted in said receptacle for actuation from in front of the instrument when the receptacle is in the aforementioned vertical position, and manually adjustable means on and coactive with the receptacle to completely cover said keyboard when the receptacle is in the aforementioned horizontal position.

3. A combined stop mounting and keyboard cover according to claim 2 wherein the receptacle is provided with means for completely closing the opening in said case when the receptacle is tilted to either one of the aforementioned positions of tilted adjustment.

4. A combined mounting and cover for the keyboard of a musical instrument employing a case upon which the keyboard is supported in a horizontal playing position, the front of the case, at 30 a point above the plane of said keyboard and slightly rearwardly of the back ends of the effective playing surfaces of the keys thereof having a longitudinally disposed forwardly facing open-

ing extending the full length of said keyboard; said combined stop mounting and keyboard cover comprising a longitudinally disposed receptacle connected to said case for tilting adjustment through the opening from a vertical position rearwardly of the back ends of the effective playing surfaces of the keys of said keyboard to a horizontal position partly covering the keyboard; said receptacle being of substantially rectangular form in cross-section and having a portion constituting the front of the receptacle when the latter is in a vertical position and a portion providing a closed back for the receptacle; a manually actuatable stop mechanism mounted in said receptacle for actuation from in front of the receptacle when the latter is tilted to said vertical position and to be disposed between the keyboard and the closed back of said receptacle when the receptacle is tilted to a horizontal position, and 20 means coactive with said receptacle to completely cover said keyboard and house said stop mechanism in the space between the keyboard and the aforementioned closed back when the receptacle is in a horizontal position.
